UNITED STATES PATENT OFFICE.

ALEXANDER MAHAFFEY READ, OF COLUMBUS, OHIO.

PULVERIZING MILL.

Original application filed December 31, 1919, Serial No. 348,506. Divided and this application filed October 9, 1920, Serial No. 415,808. Renewed November 1, 1924.

The present invention relates to certain new and useful improvements in pulverizing mills of the class in which each consists of a rotatable barrel wherein the material to be pulverized may be tumbled about with freely movable crushing bodies and be pulverized by contact therewith.

In my co-pending application, Serial No. 348,506, filed December 31st, 1919, of which this application is a division, I have disclosed a pulverizing mill comprising a barrel adapted to revolve about its longitudinal axis which is so disposed to the horizontal that the included material will tend to travel on the lower side of said barrel from the receiving to the discharging end of the mill, and in which the barrel is divided into a series of grinding compartments whereby the material is so classified that the coarser fragments are retained in the forward compartment while the finer particles are passed progressively through the succeeding compartments towards the delivery end of the machine.

The especial object of this invention is to provide a machine of the class described wherein the barrel is divided into a series of pulverizing chambers by partition screens of improved construction which effectively retain the oversize material in the respective pulverizing chambers without undue obstruction to the longitudinal flow of the fine material through the mill.

The means by which I attain this object is fully set forth in the following specification and illustrated in the accompanying drawing which is a longitudinal vertical section of the preferred embodiment of my invention.

As shown in the drawing the numeral 1 indicates a barrel adapted to revolve about its longitudinal axis which is so disposed to the horizontal that material within the barrel will tend to travel on the sides of the barrel from the receiving to the delivery end of the mill as the barrel revolves. To the barrel 1 is attached the bearing rings 2 and 3 which bear upon the rollers 4 and 5 to support the barrel for rotation. The rollers 4 and 5 are mounted in suitable journal bearings 6 and 7 which are supported upon the foundation of the mill. To the barrel 1 is attached a ring gear 8 which is engaged by a pinion 9. The pinion 9 is mounted upon a power shaft from which power is derived to revolve the barrel. The upper end

of the barrel 1 is closed by a plate 10 to which is secured a cylindrical extension 11. The extension 11 is journaled in a pillow block 12 supported upon the foundation casting 13. The pillow block 12 is provided with the customary removable cap 14 in which is formed a lubricant receptacle 15. 60 16 is a ball bearing interposed between the outer end of the pillow block 12 and the flange 17 of the cylindrical extension 11 to prevent longitudinal movement of the barrel. This cylindrical extension 11 and the plate 10 are pierced by a central bore through which extends a cylindrical trough 70 18 formed at the lower end of the feed hopper 19. Positioned within the cylindrical trough 18 is a screw conveyor 20 to the extended shaft of which is attached a suitable pulley 21 adapted to be connected with any convenient source of power to rotate the screw conveyor 20 and thereby transfer material from the feed hopper 19 to the interior of the barrel 1.

The lower end of the barrel 1 is closed by a transverse wall 22 having spherical curvature with its center of curvature located in the axis of rotation of the barrel at the forward side of said wall. The wall 22 is pierced by a plurality of screening apertures 23 adapted to permit the escape of the fully pulverized material from the interior of the mill while retaining the over size material for further grinding. The size, form and arrangement of the screening apertures 23 80 are subject to wide variation to suit the requirements of materials of different character and the desired fineness of the product. These apertures 23 preferably expand outwardly to prevent the lodgment therein of 85 fragments of material and the consequent choking of the screen.

As the fineness of grinding is directly related to the duration of time the fragments of material are retained within the mill, the axis of the barrel 1 is inclined to such an angle with the horizontal that the rate of flow of the material longitudinally of the barrel will carry said material to the discharge end at the precise moment it is pulverized to the desired degree of fineness. 100 Although I prefer to use a cylindrical barrel with its axis suitably inclined to the horizontal, the form of the barrel may be subject to wide variation without departure 105 from the spirit of my invention. Should the form of the barrel 1 be conical instead 110

of cylindrical as shown, the inclination of the axis of rotation must be so adjusted as to produce the desired rate of longitudinal flow of material within the barrel. Any 5 increase or decrease of the taper of the barrel would require an adjustment of the inclination of the axis of rotation more or less closely approaching the horizontal, and if the diameter of the discharge end of the barrel be sufficiently increased it might be necessary to incline the axis of rotation upwardly to prevent too rapid movement of material through the mill.

The friction of material against the sides 15 of the barrel cause the lower part of the mass to move upwardly with the ascending side of the barrel while the upper portion of the mass slides downward, maintaining a continuous orbital movement of the fragments of which the mass is composed, and the friction due to this movement is an important element in producing the grinding action of the mill. The grinding balls, being of greater specific gravity than the fragments 20 of the material which is being pulverized, gravitate toward the lower part of the mass and become buried beneath the lighter material. These balls are carried upward with the side of the barrel to an elevation 25 depending upon the angle of repose which is characteristic of the material under treatment, and to the centrifugal force due to the velocity of rotation. At the point of maximum elevation the material falls away 30 from the side of the barrel and the grinding balls roll upon the surface of the mass, striking fragments of material lying upon the lower side of the barrel to break them by their percussive action, thereby materially 35 assisting in pulverizing the material.

When a mass composed of freely movable fragments of various size but of the same specific gravity is agitated, the finer particles 45 tend to slip through the interstices between the larger fragments, and the larger fragments tend to float to the surface, resulting in a more or less complete stratification of the mass relative to the size of its component fragments. Due to this tendency to 50 stratification, and the inclination of the lower side of the barrel, the finer particles of material sift to the bottom of the mass and travel longitudinally of the mill tending to accumulate against the surface of the screen. 55 Owing to the slippage of the material against the surfaces of the mill this accumulation of fine material slides across the screening apertures as the mass is carried upwardly and the smaller fragments are forced through these apertures by the 60 weight of material above them. From the point of maximum elevation the material rolls downwardly, striking the surface of the screen along lines approximately normal thereto, and small fragments are car-

ried through the screening apertures without change of direction. At the same time the larger and heavier fragments, together with the grinding balls, strike upon the surface of the lower part of the screen producing 70 vibration therein which prevents the lodgment of material in the screening apertures.

As the larger fragments of material can only be broken by contact with relatively large and heavy grinding bodies, and the 75 most efficient reduction of the finer particles is accomplished by a large number of relatively small grinding bodies, and as the size of the component fragments of the material within the mill is progressively reduced as it 80 travels from the receiving towards the discharge end, it is apparent that a corresponding classification of the grinding bodies is desirable. To accomplish such classification I have divided the barrel 1 into a series of 85 grinding compartments A, B, C and D by the transverse screens 24, 25 and 26 which are similar to the screen 22 but are respectively provided with apertures of progressively decreasing dimensions, the screens 90 nearest the receiving end of the mill having the largest apertures. By this arrangement of screens the material in the successive compartments is classified relative to the size of the component fragment, and each grinding 95 compartment may be provided with grinding bodies of a size appropriate to the most efficient grinding of the material in said compartment.

I am aware that grinding mills have been 100 proposed in which the interior of the barrel is divided into a series of pulverizing chambers by transverse flat screening partitions. Screens of this character have proven to be extremely inefficient because the orbital path 105 of the fragments of material is so nearly parallel with the surface of the screen that the fine material on the forward side of the screen is carried past the screening apertures and the pressure of material against the rearward side of such a screen obstructs the 110 passage of material therethrough. By the use of screening partitions of spherical curvature, such as are here illustrated, there is 115 produced a more efficient screening action due to the inclination of the active portion of the screening surface to the orbital path of the fragments of material and to the peculiar action of the material at the back of such a screen. As the barrel revolves the 120 material adjacent the rearward side of the screens 24, 25 and 26 is deflected rearwardly by contact with the convex surfaces of said screen thereby producing a swirling or eddying movement which creates voids a, b and c in the material adjacent the lower portion of the rearward side of said screens. These voids a, b and c afford a clear passage for the material through the apertures of the screen thereby materially reducing the ob- 125

struction offered by the screens to the longitudinal flow of the fine material, and by adding to the agitation of the material increasing the effectiveness of the grinding bodies thereby still further improving the efficiency of the mill.

At the delivery end of the barrel 1 I have provided a receiving chamber 27 having flanges 28 which form dust tight joints with 10 the sides of the barrel 1, and which is provided with a spout 29 through which the material may escape from the receiving chamber to be disposed of in any preferred manner.

15 It will be understood that the broad features of this tube mill and a species thereof different from the one hereinafter claimed, are covered in the parent application above referred to. This application is directed 20 simply to one species of such a tube mill, which includes a screen of the character having a curvature, preferably spherical, transversely of the barrel.

What I claim is—

25 1. In a pulverizing mill, the combination with an approximately horizontal barrel adapted to revolve about its longitudinal axis, of a transverse screen partition dividing the interior of the barrel into separate 30 grinding chambers said screen having a spherical curvature concentric with the axis of rotation of the barrel.

2. A pulverizing mill comprising an approximately horizontal barrel, a transverse 35 screen in said barrel having a spherical curvature, said screen forming a grinding compartment within the barrel and having a screening surface so inclined to the barrel wall that together therewith it supports the 40 material within the compartment, and a multiplicity of freely tumbling crushing elements in said compartment.

3. A pulverizing mill comprising a barrel having its wall inclined to the horizontal so 45 that material within the barrel will gravitate on the wall from one end of the barrel toward the other, said barrel being revolvable about its longitudinal axis, a transverse screen forming a grinding compartment in 50 said barrel, said screen having a spherical curvature and serving together with a barrel wall to support material in the grinding compartment, and a multiplicity of freely tumbling crushing elements in said compartment.

55 4. A pulverizing mill comprising a barrel having its wall inclined to the horizontal so that material within the barrel will gravitate from one end toward the other on the 60 barrel wall, said barrel being adapted to re-

volve about its longitudinal axis, a transverse screen forming a grinding compartment in said barrel, said screen having a spherical curvature and serving together with a barrel wall to support material in the 65 grinding compartment, and a multiplicity of freely tumbling crushing elements in said compartment, the interior of said compartment being free from obstructions to the assortment of material.

70 5. A pulverizing mill comprising a barrel revolvable about its longitudinal axis and having its wall inclined to the horizontal whereby material will tend to gravitate thereon toward one end of the barrel as it 75 revolves, a plurality of transverse screens in said barrel forming grinding compartments, said screens each having a spherical curvature and serving together with the barrel wall to support material in a grinding compartment, and a multiplicity of freely tumbling crushing elements in said compartments.

75 6. A pulverizing mill comprising an approximately horizontal barrel, a transverse 80 screen in said barrel curved transversely of the barrel, said screen forming a grinding compartment within the barrel and having a screening surface so inclined to the barrel wall that together therewith it supports the 85 material within the compartment, and a multiplicity of freely tumbling crushing elements in said compartment.

7. A pulverizing mill comprising a barrel having its wall inclined to the horizontal so 90 that material within the barrel will gravitate on the wall from one end of the barrel toward the other, said barrel being revolvable about its longitudinal axis, a transverse 95 screen forming a grinding compartment in 100 said barrel, said screen being curved transversely of the barrel and serving together with a barrel wall to support material in the grinding compartment, and a multiplicity of 105 freely tumbling crushing elements in said compartment.

8. A pulverizing mill comprising a barrel revolvable about its longitudinal axis and having its wall inclined to the horizontal 110 whereby material will tend to gravitate thereon toward one end of the barrel as it revolves, a plurality of transverse screens each being curved transversely of the axis of the barrel and serving together with the barrel wall to support material in a grinding compartment, and a multiplicity of freely 115 tumbling crushing elements in said compartments.

In testimony whereof, I affix my signature.
